Patented Aug. 15, 1961

191,153

BLENDER POWER UNIT

Robert I. Gresens, Rochester, N.Y., and Paul O. Rawson,
Jr., Trumbull, Conn., assignors to General Electric
Company, a corporation of New York

Filed Mar. 27, 1961, Ser. No. 64,506

Term of patent 14 years

(Cl. D89—1)

Des. 191,153

PAGE 2

Fig. 2.

Fig. 3.

Fig. 4.

FIG. 1 is a perspective view of a blender power unit embodying our design;

FIG. 2 is a side elevation view of the blender power unit;

FIG. 3 is a top plan view of the blender power unit;

FIG. 4 is a front elevation view of the blender power unit.

The dominant features of the design reside in the portions shown in full lines.

We claim:

The ornamental design for a blender power unit, substantially as shown and described.
